TERRAZZO GRINDER.

Harold J. Pond and Daniel A. Arones, Minneapolis, Minn., assignors to Advance Machine Company, Minneapolis, Minn., a corporation of Minnesota

Application June 21, 1947, Serial No. 756,156

13 Claims. (Cl. 51—180)

1

Our invention relates to terrazzo grinders and has for an object to provide a grinder which can be conveniently used for grinding vertical surfaces such as, stair risers, baseboards, wainscot borders, and other terrazzo wall surfaces.

An object of the invention resides in providing a grinder which will cover an extended area without resetting.

A still further object resides in providing a grinder having a grinding wheel which may be easily moved toward and from the work without resetting the machine.

Another object of the invention resides in providing a grinder which will follow the wall surface without the necessity of setting the machine accurately with respect to the surface to be ground.

An object of the invention resides in providing a grinder which may be used for grinding inclined surfaces or surfaces out of plumb.

A still further object of the invention resides in providing a grinder in which the grinding wheel when moved toward the surface to be ground will be maintained parallel to said surface.

Other objects of the invention reside in the novel combination and arrangement of parts and in the details of construction hereinafter illustrated and/or described.

In the drawings.

Fig. 1 is a front elevational view of a terrazzo grinder illustrating an embodiment of our invention.

Fig. 2 is a side view of the structure shown in Fig. 1 with certain of the parts in altered position.

Fig. 3 is a side view similar to Fig. 2 showing the parts in still different positions.

Fig. 4 is a fragmentary front elevational view of a portion of one of the arms of the invention and showing the method of mounting the wheel head, said view being drawn to a greater scale than Figs. 1, 2 and 3.

Fig. 5 is a sectional view taken on line 5—5 of Fig. 4.

Fig. 6 is a longitudinal side elevational sectional view of the joint of the arms of the invention and the power transmission mechanism therein, said view being drawn to the same scale as Fig. 5.

Fig. 7 is a plan sectional view taken on line 7 of Fig. 6.

Fig. 8 is a cross sectional view taken on line 8—8 of Fig. 6.

The invention proper comprises a base 10 on which is mounted a motor 11. Motor 11 has connected to it an arm 12 which in turn has pivotally connected to it by means of a joint

2

20 another arm 13. The arm 13 has attached to it at its free end a grinding head 14 which supports a grinding wheel 15. These parts will now be described in detail.

5 The base 10 comprises two A-shaped end frames 16 and 17 which are identical in construction. Only the A frame 16 which is shown in Fig. 1 will be described in detail. This frame consists of parallel frame members 18, converging frame members 19, and a horizontal frame member 21 connected thereto. A cross frame member 22 is welded to the parallel frame members 18. The base 10 further includes two longitudinal frame members 23 which are welded to the frames 16 and 17.

10 The base 10 is supported on four wheels 24 and 25 which extend transversely of said base and of which the wheels 25 are disposed inwardly of the frame members 18 of the frame 17. These wheels

15 are mounted on lugs 26 which extend downwardly from the frame member 22 of said frame. Bolts 27 extend through said wheels and are attached to the lugs 26 and form axles on which said wheels are rotatably mounted. The wheels 24 are

20 similarly mounted on bolts 28 which are attached to lugs 29. These lugs are welded to extensions 31 formed on the cross frame member 22 of frame 16. This construction brings the said wheels 24 outwardly near the outermost edges of the base

25 10. By means of this construction the entire grinder may be moved laterally when resting on the wheels 24 and 25 which permits of moving the grinder along the surface to be ground in a manner which will be presently more fully described.

30 The base 10 may be moved longitudinally by means of the following construction. Pivoted to the two parallel frame members 18 of the frame 17 are two levers 32. These levers have bolts 33 extending through the same and which are screwed into the said frame members. The upper ends of the levers 32 have welded to them a handle 34 by means of which the said levers may be moved from the full line position to the dotted line position shown in Fig. 2. The lower ends 35 of the levers 32 have mounted on them wheels

35 36. Bolts 37 extend through these wheels and are screwed into the ends 35 of the levers 32 and form axles on which said wheels rotate. The ends 35 of said levers are angularly disposed with reference to the levers proper so that the wheels 36

40 when the said levers are in the position shown in full lines in Fig. 3 become raised above the level of the surface of which the device rests.

45 35 When the handle 34 is moved to its dotted line

50 35 the wheels 36 become lowered below the level of the surface of which the device rests.

55 35 When the handle 34 is moved to its dotted line

position its wheels 36 are swung downwardly to floor level as shown in Fig. 2. Stops 38 on the end frame 17 limit the swinging movement of the lower ends 35 of the levers 32. Further swinging movement of the handle 34 causes the wheels 24 and 25 to become raised off from the surface on which the device is disposed and permits of wheeling the device longitudinally by means of the wheels 36. A clip 30 holds the lever 32 in its retracted position.

The motor 11 of the invention is supported by means of a shaft 39, which is flattened at its ends as designated at 41 in Fig. 1. Pivotally secured to the ends of the said shaft by means of bolts 42 are two legs 43 and 44. These legs are provided with slots 45 which are adapted to receive bolts 46 extending through the same. The bolts 46 are threaded into brackets 47 welded to the horizontal frame members 21 of the frames 16 and 17. The bolts 42 extend through off-sets 48 formed on the legs 43 whereby the legs 43 and 44 straddle the two end frames 16 and 17. By means of this construction the shaft 39 may be maintained horizontal as shown in Fig. 2 or the same may be raised at either end and tilted to the positions shown in full and dotted lines in Fig. 3. By tightening the bolts 46 the shaft 39 may be held in any angular adjusted position within the limits afforded by the lengths of the slots 45.

Mounted on the shaft 39 are two bearings 49 which are secured together at their lower ends by means of a flange 51. This flange is bolted by means of bolts 52 to the motor 11. The upper ends of the bearings 49 have secured to them by means of screws 53 a longitudinally extending bar 54. Mounted between the bearings 49 and secured to the shaft 39 is a sleeve 55. This sleeve has bolted to it two blocks 56 which support a longitudinal bar 57. Bars 54 and 57 are substantially the same width and overlie one another when the arm 12 is in elevated position. A torsion coil spring 58 encircles the sleeve 55 and has its ends 61 and 62 crossed and straddling the two bars 54 and 57. Spring 58 is normally under tension so that when the parts are normally at rest the ends 61 and 62 of said spring engage the bars on opposite sides and hold the parts in upright position. When the arm 12 is normally swung from one side to the other bar 54 is disengaged from one end of the spring 58 and engages the other end to further tension the said spring. This end of the spring then leaves the bar 57. It will thus become readily comprehended that the weight of the arm and the structure supported thereby is counterbalanced through the spring 58.

The arm 12 as shown in Figs. 1 and 2 is constructed from two channel members 63 which at their lower ends are welded to two cross bars 64. These cross bars are secured to the end bell 65 of the motor 11 by means of cap screws 66. The said channel members are attached at their other ends to a case 67 by means of cap screws 68. These cap screws extend through slots 69 in the webs of the channel member 63 and are threaded into the case 67. The case 67 has two flats 71 on which the channel members 63 rest. By means of this construction the case 67 may be moved toward and from the motor 11 to adjust the belt and held in adjusted position by means of the cap screws 68.

Within the case 67, as shown in detail in Fig. 6, is rotatably mounted a shaft 72. This shaft is journaled in two ball bearings 73 and 74 which are mounted in said case. The bearing 73 is received in a bore 75 in the case 67 and butts

against a shoulder 76 formed in said case. A lock nut 77 clamps the said bearing against the shoulder 76. Bearing 74 is received in a bore 78 in said case in alignment with the bore 75. This bearing is however free to move within the bore 78. A cover 79 closes the bore 78 and when removed gives access to the bearing 74. Mounted on the shaft 72 between the two bearings 73 and 74 is a sheave 81 which receives a belt 82 disposed within the interior of the arm 12. This belt passes over another sheave 83 on the rotor shaft 84 of the motor 11. By means of this construction the shaft 72 is driven from the motor 11. The bearing 75 butts up against a collar 85 of the shaft 82. Sheave 81 butts up against the bearings 73 while a sleeve 86 lies between the bearing 74 and said sheave. A nut 87 screwed on the end of the shaft 72 holds the parts in proper assembled relation and retains the bearing 74 in operative position within the bore 78.

The arm 13 includes a housing 88 having a transverse bore 89 in the same. In this bore are mounted two ball bearings 91 and 92 which are held in spaced relation by means of a sleeve 93 disposed between the same. The bearing 91 butts up against a shoulder 94 formed in the housing 88 at the end of the bore 89. A nut 95 screwed into the end of said bore holds the two bearings in place therein. The shaft 72 extends into the housing 88 and extends through the two bearings 91 and 92. Bearing 91 fits up against a sleeve 96 which fits against a shoulder 190 on the shaft 72. A bevel gear 97 butts up against the said bearing and is held in position by means of a key 98 and a lock nut 99 screwed upon the end of the shaft 72. By means of the housing 88, the case 67, the shaft 72 and the various bearings associated with said shaft the joint 20 previously referred to is formed between the two arms 12 and 13 permitting the said arms to swing relative to one another about the axis of the shaft 72.

The housing 88 has a branch 102 extending at right angles to the axis of the joint 20. This branch has a chamber 103 within the same and in which the bevel gear 97 is disposed. The said branch has two bores 104 and 105 formed therein which are co-axial and which communicate with the chamber 103. In the bore 104 is mounted a ball bearing 106 while in the bore 105 is mounted a ball bearing 107. The bearing 107 butts against a shoulder 108 in the branch 102 of housing 88 and is held in place therein by means of a sleeve 109 which is threaded to screw into the outer end of the bore 105 and which is held in fixed relation therein by means of a lock nut 111. Journalled in the bearings 106 and 107 is a shaft 112. This shaft has a shoulder 113 against which the bearing 107 butts. A bevel gear 114 extends up to the bearing 107 and is held from rotation by means of a key 115. This bevel gear meshes with the bevel gear 97 on shaft 72. A sleeve 116 on the shaft 112 lies between the gear 114 and the bearing 106. A nut 117 on the end of the shaft 112 holds the parts in assembled relation on said shaft.

The arm 13 in addition to the housing 88 includes a mounting 119 which is disposed at the end thereof opposite said housing. This mounting is in the form of a yoke having two side members 121 and 122 and a connecting member 123 therebetween best shown in Fig. 4. A bolt 124 connects the two side members 121 and 122 together and holds them in proper spaced relation. The arm 13 further includes three parallel links 125, 126, and 127. The links 125 and 126

are pivoted to the side members 121 and 122 of the mounting 119 by means of bolts 128 which extend through said side members and are screwed into blocks 129 secured to the ends of said links. The other ends of the said links have attached to them blocks 131 which straddle a lug 132 formed on the branch 102 of housing 88. A pin 133 extends through said blocks and boss and pivotally connects the ends of the said links to the housing 88 which forms a portion of the joint 20. A plate 130 extends across the blocks 131 and is secured to said blocks by means of cap screws 134 which extend through said plate and are threaded into the said blocks. By means of this construction the ends of the links 125 and 126 are securely tied together. The link 127 is connected to the mounting 119 and to the housing 88 in much the same manner as the links 125 and 126. The link 127 is constructed with a block 135 at its upper end which extends between the two side members 121 and 122 of mounting 119. A pintle 136 extends through said side members and block and pivotally supports the upper end of said link to the mounting. The lower end of link 127 has a block 137 attached to it which is received between two lugs 138 and 139, formed on the upper portion of the housing 88. A pintle 141 extends through the said lugs and block and pivotally supports the lower end of the said link. By means of the construction forming the arm 13 the mounting 121 may be moved in any direction from left to right and vice versa as viewed in Fig. 2 from the dotted line position to full line position. The arm 13 may be swung about the axis of the joint 20 and the mounting may be moved toward and from the surface of the wall being worked by means of handle 142. This handle is attached to a cross bar 143 extending between the two side members 121 and 122 of mounting 119. The weight of the arm 13 is counter-balanced by means of a counter-balanced weight 144 which is slidably mounted on a rod 145 and held in position thereon by means of a set screw 146. The rod 145 is attached to a boss 147 by means of a set screw 148. Boss 147 has a flange 149 formed on the same which is secured to the end of the branch 102 of case 88 by means of screws 151 as best shown in Fig. 6.

Supported by the mounting 119 is the grinding head 14 which includes a housing 153 best shown in Fig. 5. This housing has a transverse portion 154 and a longitudinal portion 155. Said housing has a chamber 156 within the same. In the transverse portion 153 are formed two co-axial bores 157 and 158 which receive ball bearings 161 and 162. The ball bearing 162 butts up against a shoulder 163 in the housing 153 and projects outwardly beyond the end of said housing. Encircling said bearing upon the projecting portion thereof is a collar 164 which has a shoulder 165 butting against the outer end of the bearing 162. This collar is secured to the housing 154 by means of screws 160 shown in detail in Fig. 4. Mounted for rotation in the bearings 161 and 162 is a shaft 166. This shaft has an enlarged head 168 formed on the outer end of the same. Encircling the said shaft and disposed adjacent said head is a collar 169 which has a slinger 171 formed on the outer portion of the same. A spacer 172 also encircles the shaft 166 and butts against the bearing 162 mounted on the shaft 166. Mounted on the shaft 166 and disposed within the chamber 156 is a bevel gear 173. This gear is keyed to the shaft by means of a key 174 and extends up to the bearing 162.

6 A sleeve 175 encircles the said shaft 166 and is disposed between the end of the gear 173 and the bearing 161. A nut 176 screwed upon the end of the shaft 166 holds the parts in assembled relation. Mounted upon the end of the shaft 166 is the grinding wheel 15 which is cupped shaped in form. This wheel is mounted upon the head 168 of shaft 166 and butts against the collar 169. Said wheel is held in place on shaft 166 by means of a screw 178 which has a flanged head 179 engaging the innermost portion of said wheel. The screw 178 screws into threads 181 formed in the end of the shaft 166. In this manner the wheel 15 is held mounted upon the end of the shaft 166.

The grinding head 14 is mounted for universal movement with respect to the mounting 119 by means of a universal joint indicated in its entirety by the reference numeral 182. This joint includes a ring 183 which encircles the collar 164. Screws 184 are threaded into the ring and pivots 185 formed on the ends of the same are received in sockets 186 formed in the collar 164. This construction is best shown in Figs. 4 and 5. The two side members 121 and 122 of the mounting 119 have threaded in them screws 187 which are similar to the screws 184 and which have pivots 188 received within sockets 189 in the ring 183. These pivots are at right angles to the pivots 185. By means of this construction the head 14 may be moved about to cause the grinding surface 191 to conform to the plane of the surface being ground.

For the purpose of manipulating head 152 a knob 192 is employed. This knob has a boss 193 which is received in the outermost end of the bore 157 of housing 153. A set screw 194 holds the said knob in place.

Water is furnished to the grinding wheel 15 by means of the following construction. A water pump 195 is mounted on the arm 12. This water pump has a pulley 196 mounted on the drive shaft 190 of the same. A belt 197 passes over this pulley and another pulley 198 on the armature shaft 84 of motor 11. The pump 195 has an inlet tube 199 connected to it which in turn is connected to a water tank 201. Tank 201 is mounted on brackets 202 secured to the A-frame 17. Pump 195 has an outlet tube 203 connected to it which in leads the water to the grinding head 152.

For the purpose of conducting the water to the wheel 15 the knob 192 is constructed with a water passageway 204 having a nipple 205 screwed into the same. The tube 203 is connected to the said nipple. The shaft 166 in grinding head 152 is formed with a bore 206 extending completely through the same. This bore communicates with a bore 207 in the screw 178. A tube 208 is disposed within the bores 206 and 207. This tube has an enlarged portion 209 at its innermost end which is screwed into threads 211 formed in the knob 192. The interior of the tube 208 communicates with the passageway 204. A felt washer 212 encircles the tube 208 and forms a fluid tight connection between the nut 176 and the enlarged portion 209 of said tube. By means of this construction water is prevented from entering the interior of the housing 153.

70 The shaft 166 is driven in the following manner. In the longitudinal portion 155 of housing 153 is formed a bore 213. In this bore is mounted two ball bearings 214 and 215. Bearing 214 bears against a shoulder 216 formed in the said

portion of the housing. A spacer 217 holds the two bearings in proper relation within the bore 213. A threaded sleeve 218 is screwed into the end of the portion 155 of housing 153 and holds the various parts in position. Rotatably mounted in the bearings 214 and 215 is a shaft 219. This shaft has a shoulder 221 against which the bearing 214 butts. A bevel gear 222 is mounted on the end of the shaft 219 and is keyed thereto by means of a key 223. This gear is held in place upon the end of said shaft by means of a nut 224 which is screwed upon said shaft. The gear 222 meshes with the gear 173.

The two shafts 219 and 112 are connected together by means of a flexible shaft 225. This shaft has secured to it at its lower end a connector 226 which is formed with a flat 227. Connector 226 is adapted to be received within a socket 228 in the end of the shaft 112. A slot 229 milled in the end of the shaft 112 receives a key 231 which engages the flat 227 and holds the shaft 225 from rotation. A collar 232 encircles the shaft 112 and has a set screw 233 in the same which engages the said shaft and clamps the parts in position. By means of this construction the one end of the shaft 225 is connected to the shaft 112 and may slide longitudinally relative thereto. The other end of the shaft 225 has secured to it a connector 230 which is connected to the end of the shaft 219. This connector has a tongue 239 which fits into a slot 241 in the end of the shaft 219. A collar 242 similar to the collar 232 holds the parts assembled. Encircling the shaft 225 is a flexible tubular case 234. This case has attached to the ends of it nipples 235 and 236 which are secured to the sleeve 109 and the sleeve 218 respectively. A screw 237 holds the nipple 235 attached to sleeve 109 while threads 238 on the end of the nipple 236 attach the same to the sleeve 218.

The method of using the invention is as follows. The handle 34 is first tilted back to the position shown in dotted lines in Fig. 2 and until the lower end 35 of the lever 32 engages the stop 38. Wheels 36 are now in a position to engage the ground. Further movement of the handle 34 in a downward direction tilts the base 10 upwardly and raises the wheels 24 and 25 above the floor on which the machine is setting. The grinder may now be conveniently wheeled about to the position where the same is to be used. Upon movement of the handle 34 in the opposite direction support of the grinder is transferred to wheels 24 and 25 and the wheels 36 raised above the floor. When in such position the lever 32 is held in place by clip 30. The motor 11 is now energized and the handle 142 grasped by one hand and knob 192 by the other. Movement of the arms 12 and 13 is now controlled by the handle 142 and the locality of grinding determined thereby. By moving the handle 142 toward the surface to be ground and by manipulating knob 192 the actual grinding is controlled.

The advantages of the invention are manifest. With our improved terrazzo grinder, grinding may be easily and quickly accomplished. Extended areas may be ground without moving the entire machine. The machine does not have to be positioned closely to the surface to be ground. The grinder does not have to be accurately aligned with the surface to be ground. The parts of the grinder are counterbalanced in a manner such that the grinding wheel may be moved about during grinding without undue effort. In the movement of the grinding wheel toward and from the

wall or surface being ground the wheel travels in a parallel direction. The angularity of the plane of movement of the grinding wheel may be easily varied within considerable limits. The wheel is mounted rigidly on the spindle, with the spindle floating, thus permitting the wheel to run at the high speeds necessary for maximum efficiency. This also allows the wheel to be dressed to the desired shape without removing it from the spindle, and permits the use of a round edge wheel for grinding of cove bases.

Changes in the specific form of our invention, as herein described, may be made within the scope of what is claimed without departing from the spirit of our invention.

Having described our invention, what we claim as new and desire to protect by Letters Patent is:

1. In combination, a support, an arm, a pivotal connection between said arm and said support, a second arm, a joint between said arms, the axis of said joint being parallel to the axis of said pivotal connection, said joint including a member movable with said second arm, said second arm including a mounting at the end thereof opposite said member and parallel links pivoted to said member and to said mounting for swinging movement about parallel axes disposed at right angles to a plane containing the axis of said joint, a grinding head carried by said mounting and including a grinding wheel and power transmission means for driving said grinding wheel.

2. In combination, a support, an arm, a pivotal connection between said arm and said support, a second arm, a joint between said arms, the axis of said joint being parallel to the axis of said pivotal connection, said joint including a member movable with said second arm, said second arm including a mounting at the end thereof opposite said member and parallel links pivoted to said member and to said mounting for swinging movement about parallel axes disposed at right angles to a plane containing the axis of said joint, a grinding head including a shaft having its axis parallel to the axis of said joint, a bearing for said shaft carried by said mounting, a shaft carried by said joint, means for rotating said second shaft, and a flexible shaft extending along said links, said flexible shaft being driven from said second shaft and driving said first shaft.

3. In combination, a support, an arm, a pivotal connection between said arm and said support, a second arm, a joint between said second arm and said support, the axis of said joint being parallel to the axis of said pivotal connection, said joint including a member movable with said second arm, said second arm including a mounting at the end thereof opposite said member and parallel links pivoted to said member and to said mounting for swinging movement about parallel axes disposed at right angles to a plane containing the axis of said joint, a grinding head including a shaft having its axis parallel to the axis of said joint, a bearing for said shaft, a ring encircling said bearing, pivot means between said ring and bearing having its axis at right angles to the axis of said shaft, other pivot means between said ring and mounting and having its axis at right angles to a plane containing the axis of said shaft and said first named pivot means and power transmission means for driving said first named shaft.

4. In combination, a support, an arm, a pivotal connection between said arm and said support, a second arm, a joint between said arms, the axis of said joint being parallel to the axis of said

pivotal connection, said joint including a member movable with said second arm, said second arm including a mounting at the end thereof opposite said member and parallel links pivoted to said member and to said mounting for swinging movement about parallel axes disposed at right angles to a plane containing the axis of said joint, said links being spaced longitudinally of the axis of said joint, a grinding wheel at the end of said second arm and having its axis parallel to the axis of said joint and power transmission means for driving said grinding wheel.

5. In combination, a support, an arm, a pivotal connection between said arm and said support, a second arm, a joint between said arms the axis of said joint being parallel to the axis of said pivotal connection, said joint including a member movable with said second arm, said second arm including a mounting at the end thereof opposite said member and three spaced parallel links, pivots between said links and member and between said links and said mounting, the axes of said pivots being parallel and being disposed at right angles to a plane containing the axis of said joint, the pivots at each end of two of said links being co-axial, a grinding head carried by said mounting and including a grinding wheel and power transmission means for driving said grinding wheel.

6. In combination, a support, an arm, a pivotal connection between said arm and said support, a second arm, a joint between said arms, the axis of said joint being parallel to the axis of said pivotal connection, said joint including a member movable with said second arm, said second arm including a mounting at the end thereof opposite said member and three spaced parallel links arranged in the form of a triangle, pivots between said links and member and between said links and said mounting, the axes of said pivots being parallel and being disposed at right angles to a plane containing the axis of said joint, the pivots at each end of two of said links being co-axial, a grinding head carried by said mounting and including a grinding wheel and power transmission means for driving said grinding wheel.

7. In combination, a support, an arm, a pivotal connection between said arm and said support, a second arm, a joint between said arms, the axis of said joint being parallel to the axis of said pivotal connection, said joint including a member movable with said second arm, said second arm including a mounting at the end thereof opposite said member and three spaced parallel links arranged in the form of a triangle, pivots between said links and member and between said links and said mounting, the axes of said pivots being parallel and being disposed at right angles to a plane containing the axis of said joint, the pivots at each end of two of said links being co-axial, a grinding head carried by said mounting and including a grinding wheel and a power transmission shaft for driving said grinding wheel, said shaft being disposed substantially within the confines of said triangle.

8. In combination, a support, comprising two spaced supporting members, a shaft extending across said supporting members, guide means acting between each of said supporting members and the shaft for guiding either end of the shaft for up and down movement to an extent greater than the other end of the shaft, clamp means for holding the shaft in any of its positions, a pair of jointed arms, pivot means between said shaft and one of said arms, a grinding wheel

carried by the other of said arms and power transmission means for driving said grinding wheel.

9. In combination, a support, a fixed shaft carried by said support, a pair of jointed arms, pivot means between said shaft and one of said arms, a grinding wheel carried by the other of said arms, an abutment on said shaft, a coil spring encircling said shaft, the ends of said spring engaging said abutment on opposite sides thereof and in a manner to cause tensioning of the spring upon movement away from said abutment, a shoulder movable with the pivoted arm and engaging one end of said spring, a second shoulder movable with the pivoted arm and engaging the other end of said spring, said shoulders upon movement of the pivoted arms in opposite directions moving one or the other of the ends of the spring away from said abutment to tension the spring, and said spring urging said ends back into engagement with said abutment and said arm into normal position and power transmission means for driving said grinding wheel.

10. In combination, a support, an arm, a pivotal connection between said arm and said support, a second arm, a joint between said arms, the axis of said joint being parallel to the axis of said pivotal connection, said joint including a member movable with said second arm, said second arm including a mounting at the end thereof opposite said member and parallel links pivoted to said member and to said mounting for swinging movement about parallel axes disposed at right angles to a plane containing the axis of said joint, a grinding head, including a shaft having its axis parallel to the axis of said joint, a bearing for said shaft, a universal joint between said bearing and mounting and power transmission means for driving said shaft.

11. In combination, a support, an arm, a pivotal connection between said arm and said support, a second arm, a joint between said arms, the axis of said joint being parallel to the axis of said pivotal connection, said joint including a member movable with said second arm, said second arm including a mounting at the end thereof opposite said member and a link pivoted to said member and to said mounting for swinging movement about parallel axes disposed at right angles to a plane containing the axis of said joint, a grinding head carried by said mounting and including a grinding wheel and power transmission means for driving said grinding head.

12. In combination, a support comprising two spaced supporting members, a shaft extending across said supporting members, guide means acting between each of said supporting members and the shaft for guiding either end of the shaft for up and down movement, clamp means for holding said shaft in angularly adjusted position and a grinder pivotally mounted on said shaft and having a grinding wheel disposed remotely from said shaft and adapted to be shifted in position upon swinging of the grinder about said shaft.

13. In combination, a support, an arm, a pivotal connection between said arm and said support, a second arm, a joint between said arms, the axis of said joint being parallel to the axis of said pivotal connection, said joint including a member movable with said second arm, said second arm including a mounting at the end thereof, a grinding wheel carried by said mounting and a pivot between the second arm and said member, said pivot having an axis at right angles to a plane

11

containing the axes of said pivotal connection and said joint and guiding said grinding wheel for movement toward and from the surface being ground.
